Fig. 2

UNITED STATES PATENT OFFICE.

CLARENCE B. CUTLER, OF CASTLETON, ASSIGNOR TO SEYMOUR CHAIR COMPANY, OF WEST TROY, NEW YORK.

DESIGN FOR A CHAIR.

SPECIFICATION forming part of Design No. 12,293, dated June 7, 1881.

Application filed December 18, 1880. Term of patent 7 years.

To all whom it may concern:

Be it known that I, CLARENCE B. CUTLER, of the village of Castleton, county of Rensselaer, and State of New York, have invented a 5 new and useful Improvement in Ornamental Designs for Chairs, of which the following is a specification.

My invention relates to a manner of producing an ornamental design for chairs, as illustrated in the accompanying photograph, forming a part of this specification, and in which the letter-reference in each designation refers to the same parts of the design, Figure 1 illustrating my invention of a design as applied to 15 an arm-chair, and Fig. 2 as appearing in a chair without arms.

My invention of a design consists in the combination of the scrolls B B, the recesses e e, with the flat surfaces n² n² m² m², and the vertical fluting ornamentation shown at d' d', arranged between the two flat surfaces on the front of the posts P' P and above the seat.

My invention of a design also consists in the manner of ornamenting the top rail of the back, 25 (designated at F'), and produced by means of the arched top A, arranged between the two flat surface-lines shown at y y, with the front face of the arch ornamented with a radiate sun, (shown at S;) also, in the combination of the 30 arch A, its radiate sun S, the flat-line surfaces y y, arranged at each side of the arch, between the latter and the posts, and the horizontally-recessed band of fluting on the front face of the top rail, below the arch, (designated at a.)

My invention of a design also consists in the manner of ornamenting the base or bottom rail 35 of the chair-back, (designated at P³,) and produced by the double reversing ogee curves C'' C'', formed on the lower edge of this member; 40 also, in the combination of these curves with the oval opening formed in the bottom rail at the union of the reversing curves shown at O'', and the recessed row of fluting f, horizontally formed in the front face of the lower rail, 45 (designated at M.)

My invention of a design also consists in the manner of arranging an ornamental diagonal brace, a'', in combination with the chair-posts P' and P'', the foot-round a', and the side of 50 the seat-frame a⁵, so as to produce on each side

of the chair the ornamental hypotenused division of the space bounded by the front and back posts, the sides of the seat-frame, and the foot-round.

My invention also consists in the design for 55 the seat-frame of the chair at the front, as designated at B², and produced by the horizontal division of this member in two parts, A² and A³, the front of the upper portion, A², having on its face a filleted band of fluting, (shown at 6c x,) and the lower portion, A³, having at the front a straight filleted top edge, and its lower edge ornamented with a central half oval curve, p', and on each side of the latter, and between it and the posts, the ogee curves p² p², there 65 being arranged between the upper and lower horizontal parts of the frame-front the vertical post-rounds p³ p³ p³.

My invention of a design for a chair consists, in combination, of the ornamental form and ornamentation of the posts P' P' and P'' P'', the top rail of the back, (designated at F,) the bottom rail of the back P³, the slats t t t, the sides of the seat-frame a⁵, the front of the seat-frame B³, the seat S'', the diagonal brace a'', the foot-round a', and the central round, R.

I am well aware of the fact that a diagonal brace has been used in the space between the seat-rail, corner-post, and the foot-rail, and that the back post has been extended into the area 80 thus formed, so as to join the diagonal brace at its center and divide the area bounded by the seat-rail, corner-posts, and foot-rail into three parts. This construction, however, has not the ornamental effect produced by my hypotenused division of this area, as is quite apparent when the two arrangements are compared.

Having thus described my invention, what I claim, and desire to secure by Letters Patent, is—

1. The design for the ornamentation of that part of the top and front of the back posts of a chair which is above the seat, and consisting of the forwardly-projected scroll B, the 95 curved recess e below the latter, the vertical fluting d', the flat surface n² above the latter, and between it and the recess, the flat surface m² below the fluting, and between the latter and the seat, as shown and described.

2. The design for the ornamentation of the top rail of a chair-back, consisting of the arch A, and the plain horizontal surfaces y y upon each side of the arch, and between it and the posts, with the arch having on its face the radiate sun S, and the front surface of the rail ornamented with the horizontal row of recessed fluting below the arch at a, as shown and described.
3. The design for the ornamentation of the bottom rail of a chair-back, and consisting of the two reversing ogee curves formed on its lower edge, as shown at C'' C'', the oval opening formed in the rail above where the curves meet, (designated at O''), and the recessed band of fluting M, formed on the front surface of the rail above the curves, as shown and described.
4. The design for chairs, consisting of the diagonal brace a'', arranged across the space at each side of the lower portion of the chair enclosed by the seat-frame, the front and back posts, and foot rail or round, substantially as specified.
5. The design for the ornamentation of the

seat-frame of a chair at the front of the frame, 25 and consisting of the longitudinally-divided portions A² A³, their form and surface ornamentation, as shown, and the intermediate vertical post-rounds p³ p³ p³, as shown and described.

6. My invention of a design for a chair, consisting, in combination, of the ornamental form and ornamentation of the front and back posts, P' P'', the top rail of the back F', the bottom rail of the back P³, the vertical back slats, t t t, 35 the front of the seat-frame B², the hypotenused division of the space at the side of the chair, inclosed by the side of the seat-frame, the front and back posts, and foot-rail, by means of the diagonal brace a'', and the seat 40 S'', as shown and described.

Signed at Troy, New York, this 2d day of December, 1880.

CLARENCE B. CUTLER.
